United States Patent Office

Des. 179,568
Patented Jan. 22, 1957

179,568

PIN OR SIMILAR ARTICLE

Jesse Walton Hand, Cape Girardeau, Mo.

Application June 13, 1955, Serial No. 36,477

Term of patent 14 years

(Cl. D45—19)

FIG. 1

FIG. 2

FIG. 3

Fig. 1 is a front elevational view of a novel pin or similar article, showing my new design;
Fig. 2 is a rear elevational view thereof; and
Fig. 3 is an edge view thereof.
What I claim is:
The ornamental design for a pin or similar article, as shown.
